CLAIM

The ornamental design of a fluid collection apparatus, as shown and described.

DESCRIPTION

FIG. 1 is a perspective view of a fluid collection apparatus configured in accordance with the present invention;

FIG. 2 is a left side view of the fluid collection apparatus illustrated in FIG. 1;

FIG. 3 is a right side view of the fluid collection apparatus illustrated in FIG. 1;

FIG. 4 is a back view of the fluid collection apparatus illustrated in FIG. 1;

FIG. 5 is a front view of the fluid collection apparatus illustrated in FIG. 1;

FIG. 6 is a top view of the fluid collection apparatus illustrated in FIG. 1; and,

FIG. 7 is a bottom view of the fluid collection apparatus illustrated in FIG. 1.

The broken lines in the drawing are included for the purpose of illustration and form no part of the claimed design.
